Primary Examiner — Susan Bennett Hattan*Assistant Examiner* — Leanne Was(74) *Attorney, Agent, or Firm* — Flaster/Greenberg P.C.**CLAIM**

The design of a container overcap, as shown and described.

DESCRIPTION

FIG. 1 is a top perspective view of a container overcap showing a new design, with portions of the article shown in broken lines;

FIG. 2 is a top plan view of the container overcap of FIG. 1; FIG. 3 is a bottom plan view of the container overcap of FIG. 1;

FIG. 4 is a front elevation of the container overcap of FIG. 1; FIG. 5 is a rear elevation of the container overcap of FIG. 1; FIG. 6 is a left side elevation of the container overcap of FIG. 1; and,

FIG. 7 is a right side elevation of the container overcap of FIG. 1.

The broken lines shown in the various figures illustrate portions of the article that form no part of the claimed design.
